(57) **CLAIM**

The ornamental design for a food product, as shown and described.

DESCRIPTION

FIG. 1 is a side view of a food product in accordance with this invention, wherein the opposite side view of the food product is a mirror image of FIG. 1 and therefore not shown.

FIG. 2 is a left elevational view of the food product of FIG. 1

FIG. 3 is a right elevational view of the food product of FIG. 1.

FIG. 4 is a top view of the food product of FIG. 1; and,
FIG. 5 is a bottom view of the food product of FIG. 1.
